DESIGN FOR A TOWEL RACK OR THE LIKE

Earl J. Coffed, Depew, N. Y.

Application April 24, 1945, Serial No. 119,167

Term of patent 14 years

(Cl. D33—16)

To all whom it may concern:

Be it known that I, Earl J. Coffed, a citizen of the United States residing at Depew, in the county of Erie and State of New York, have invented a new, original, and ornamental Design for a Towel Rack or the like, of which the following is a specification, reference being had to the accompanying drawing, forming a part thereof.

Figure 1 is a side view of a towel rack showing my new design. Figure 2 is a front view thereof. Figure 3 is a perspective view, and Figure 4 is a bottom plan view thereof.

I claim:

The ornamental design for a towel rack or the like, substantially as shown.

EARL J. COFFED.
